CLAIM

The ornamental design for a curling iron, as shown and described.

DESCRIPTION

FIG. 1 is a top plan view of a curling iron showing my new design;

FIG. 2 is a right side elevational view thereof;

FIG. 3 is a bottom plan view thereof;

FIG. 4 is a left side elevational view thereof;

FIG. 5 is a front elevational view thereof; and

FIG. 6 is a rear elevational view thereof.

The electric cord member is fragmentarily illustrated in FIGS. 1-6 for ease of illustration.

UNITED STATES PATENT AND TRADEMARK OFFICE
CERTIFICATE OF CORRECTION

PATENT NO. : Des. 313,484

DATED : January 1, 1991

INVENTOR(S) : John F. Wahl and Keith W. Dirks

It is certified that error appears in the above-identified patent and that said Letters Patent is hereby corrected as shown below:

On the Cover Page:

Add inventors --Nicolo Altamore, of Rockford, Ill. and
Gregory S. Wahl, of Sterling, Ill.--.

Signed and Sealed this
Twenty-fourth Day of November, 1992

Attest:

DOUGLAS B. COMER

Attesting Officer

Acting Commissioner of Patents and Trademarks
